UNITED STATES PATENT OFFICE.

WILLIAM VAN ANDEN, OF POUGHKEEPSIE, NEW YORK.

MACHINE FOR CUTTING FILES.

Specification of Letters Patent No. 29,641, dated August 14, 1860.

To all whom it may concern:

Be it known that I, WILLIAM VAN ANDEN, of the city of Poughkeepsie, county of Dutchess, and State of New York, have invented certain new and useful Improvements in Machines for Cutting Files; and I do hereby declare the following to be a full description of the same, reference being had to the annexed drawings, and to the letters 10 of reference marked thereon, making a part of this specification, in which—

Figure I is a right hand side elevation of machine. Fig. II is a plan view of machine. Fig. III is a left hand side elevation of machine. Fig. IV is a front end elevation of machine. Fig. V is a sectional and plan view of chisel holder. Fig. VI is a side elevation of double cam.

The nature of my invention consists, first, 20 in the mode of constructing the machine in the arrangement of the cams used for tilting the hammer in order to strike two light blows of the hammer upon the chisel in order to form a tooth instead of one heavy blow which is very likely to break the chisel; second, the formation of the chisel holder the forward part of which by suitable means as hereafter described is made to press down 25 on the file blank to hold it firm while the tooth is hereby being cut and also raising it when the bed is fed forward for the chisel to operate on another tooth and which holder also allows the chisel to be depressed to the bottom of the tooth by the force of the 30 hammer and to remain depressed below the lower face of the holder while it is being lifted up for the file blank to advance and upon the chisel holder being again pressed down on the file blank forces the chisel up 35 by means of its coming first in contact with the file blank and thereby making it adjust 40 itself to the face of the file blank.

I will now proceed to describe the construction and operation of my machine.

45 A is the frame of the machine across the top of the frame and forming part of it is a table board B having a groove C cut in its upper face. This groove traverses the length 50 of the table in a slightly oblique direction from the front and right hand side of the machine to the back and left side of it. The object of this is to cause the lower half of the compound bed D by reason of a tongue A² on its lower surface to traverse the length 55 of the feed table in an oblique direction. On its upper face are two grooves b² b² from

the left to the right side obliquely across it into which fit tongues C² C² in the lower face of the upper half E of the compound bed. The object of this is to cause up or 60 forward motion by an independent motion of the positive feed against the edge of the chisel in consequence of the percussion of the hammer upon the file blank F and the difference of resisting surface of the metal 65 against the back edge of the chisel in consequence of its angle of cut wedging it forward at the time of cutting the teeth.

f² is the tang holder having hooks g² on its upper back edge, so as to hold the file 70 blank down upon the bed. The tang holder fits into a mortise hole in the bed D with just sufficient room to allow of its working up and down as the point of the file is depressed while under the action of the chisel. 75

h² is a lever jaw attached to the bed for holding against the side of the file blank while being cut.

H is a vertical guide post at the back of the frame A. In the guide way of the 80 post H works a triangular-shaped gate I, having on its longest side or hypotenuse a tongue i². This works into a groove d² in the back end of the lower half of the bed D, so that as the gate is worked by means of 85 the female screw J at the back edge of it, being forced into gear by a foot lever O at the side of the frame A with a vertical male screw K rotated by means of a saw or ratchet wheel L, secured upon its upper end, 90 and a worm M on the end of the main driving shaft N.

The compound bed is fed up and under the action of the chisel as required and drawn back again by the female screw J being thrown out of gear again by dropping the foot lever O. 95

P, P are two pawls on the main driving shaft M. These pawls as the shaft N rotates 100 operate a ratchet wheel Q, running loosely on the hammer shaft or axis R. At the side of the wheel Q is a stiffer spring S, having one end secured to the axis R and at its opposite side a detent pin S², which by its adjustment acts against a pin S³ in the axis R 105 to hold the ratchet wheel when it reacts after the file has been cut so as to preserve a uniformity of starting point in the force of the hammer in cutting the file, while the increasing force of the hammer is regulated 110 by the pawls winding up the spiral spring on the ratchet wheel one tooth or more at

each revolution of the driving shaft N and is kept at its maximum point until the file has been cut when the pawls are thrown out of gear by an intercepting bar T and lever 5 T² arranged at the side of the frame holding the hammer shaft in under them and also of the toe T³ of the hammer T⁴, so as to allow the main shaft N to continue its motion while the new file blank is being put on the 10 machine and adjusted.

5 is the chisel stock secured on an axis U² arranged on a part of the frame of the machine and which chisel stock is composed and constructed of the shell or outside part 15 X¹ the loose back X² the slide piece or nut X³ through which the loose back X² works and which back is kept firmly up to the chisel X⁴, which is placed in the space in between the loose back X² and the inside of 20 the front of the shell X¹ by means of the action of the spring X⁵ upon the back end of the loose back X², and thus enabling the chisel X⁴ to work in the said space and allow it to find its own adjustment and yet to be 25 held firmly at the angle at which it is set in order to cut the file tooth.

Y is a lever arranged in the frame of the machine A in such a manner that the front extremity lies upon and exerts its force on 30 a pin inserted in the axis of the chisel stock U² in such a manner that when the other extremity of said lever is raised by means of the cam Z on the shaft N, that it will depress the front end of the chisel holder 5 on 35 the file blank in advance of the blow of the hammer upon the blank, so that it may hold the blank down and at the same time be at rest when the hammer strikes the head of the chisel, the force of the hammer at each 40 blow causing the chisel to project down below the lower face of the chisel holder 5 and to the bottom of the tooth cut and remain so depressed below the face of said chisel holder until it is raised up as heretofore de- 45 scribed for the file blank to advance the necessary distance for another tooth, and upon the chisel holder being again pressed down on the file blank the chisel being now extended below the said surface of the holder 50 comes first in contact with the file blank and as the pressure continues causes the chisel to raise up in its seat and adjust itself to the face of the file blank all the time being held against the front inside face of the shell X¹ 55 by the pressure of the springs X⁵ on the loose back X² working in the nut or slide X³, and by this means rendering the said chisel holder 5 self adjustable as regards the chisel and the file blank.

There has always been one source of great 60 disappointment and almost a fatal defect in the using of these machines viz: the breakage of the chisel, by the force and weight of the hammer necessary to strike a blow on the chisel sufficient to cut the tooth of the 65 file as deep as required at one stroke and all attempts to remedy this defect have hereto failed. In order to avoid this I make the cam 4, which depresses the toe of the hammer handle T⁴ in order to strike the blow 70 of what may be called a double cam that is made with two projections which gives the hammer a double stroke on the chisel in cutting each tooth and thereby only using one half of the power necessary to cut the tooth 75 at one blow, thus enabling to stand much longer by having its work divided.

I do not mean to confine myself to two 80 blows if more should be necessary for the support of the chisel, nor do I mean to confine myself to the formation and use of the cam as various means may be used for lifting the hammer.

It will be perceived that this machine 85 makes but one series of cuts and may therefore be termed a right handed machine.

To make the opposite transverse cuts the machine will be made as a left-handed machine requiring therefore two machines to complete the operation of cutting the file. 90 This, however, is not absolutely necessary, but prefer it rather than make the one machine changeable to accomplish this result, and besides as many machines will be used in cutting files I do not deem it any additional expense to have some made right handed and others made left handed for the 95 purposes described.

Having described my invention and its 100 operation I will proceed to set forth what I claim and deem to secure by Letters Patent of the United States—

1. Striking a series of blows on the chisel in combination with the file blank while at a state of rest and in the same tooth for the 105 purposes as heretofore set forth and described.

2. The formation of the self adjustable chisel holder viz., by the combination of the shell X¹ the yielding or loose back X² the 110 nut or slide X³ the chisel X⁴ spring X⁵ or their equivalents for the purposes heretofore set forth and described.

WM. VAN ANDEN.
